Primary Examiner — Kevin K Rudzinski*Assistant Examiner* — Paul D Bohannon*(74) Attorney, Agent, or Firm* — Heslin Rothenberg Farley and Mesiti PC(57) **CLAIM**

The ornamental design for a seat, as shown and described.

DESCRIPTION

FIG. 1 is a perspective view of a seat in accordance with the new design;
 FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a top view thereof.

The broken lines in the drawings illustrate portions of the seat which form no part of the claimed design.

1 Claim, 6 Drawing Sheets(56)
